UNITED STATES PATENT OFFICE.

ALEX F. AMELUNG, OF SANBORN, IOWA.

ENGINE-REPAIR STAND.

1,236,246.

Specification of Letters Patent.

Patented Aug. 7, 1917.

Application filed June 9, 1916. Serial No. 102,751.

To all whom it may concern:

Be it known that I, ALEX F. AMELUNG, a citizen of the United States, residing at Sanborn, in the county of O'Brien and State of Iowa, have invented new and useful Improvements in Engine-Repair Stands, of which the following is a specification.

This invention comprehends the provision of a stand designed to support an engine for repairs or other purposes, and capable of adjustment to change the position of the engine to the convenience of the workman.

In carrying out the invention I aim to provide a stand of the above mentioned character whereby the engine can be adjusted to any position without removing it from the stand, consequently permitting one movement to turn the engine to the most advantageous position without any heavy lifting.

The nature and advantages of the invention will be better understood when the following description is read in connection with the accompanying drawing, the invention residing in the construction, combination and arrangement of parts as claimed.

In the drawing forming part of this specification like numerals of reference indicate similar parts in the several views and wherein:

Figure 1 is a perspective view of the stand.

Fig. 2 is a side elevation showing the engine or work supported thereon.

Before entering into a detail description of what is hereby shown I desire to have it understood that the same is merely illustrative of the preferred embodiment of the invention, to which I do not limit myself, and that such changes may be resorted to when desired as fall within the scope of what is claimed.

As shown in this specific instance the stand forming the subject matter of the invention embodies a base 10 preferably of rectangular formation with the sides composed of angle iron bars, the base being supported upon the rollers 11 to permit the stand in its entirety to be conveniently moved from place to place. Rising from the corners of the base are standards 12 which slightly converge inwardly, the standards at the ends of the stand being con-

nected by the downwardly curved arch-shaped members 13. These members may 55 form an integral part of the standards, or may be detachably associated therewith in any suitable manner.

A pair of annuli 14 constructed of metal and of any desired dimensions are suitably 60 spaced in parallelism, and connected together by the angle iron bars 15, the latter being arranged slightly below the transverse center of the annuli to equalize the weight. Hooked about the angle bars 15 at points 65 adjacent each annulus are iron strips 17 which are disposed horizontally and have their extremities extending toward each other. These strips are provided with a plurality of openings through which suitable bolts may be passed for the purpose of rigidly connecting the engine therewith, and by interchangeably fitting the bolts in the openings, engines of different sizes can be supported as will be readily understood. 75 The annuli are supported upon the arched-shaped members 12 and are flanged as at 18 to prevent endwise movement and casual rearrangement of the parts.

In practice the engine to be repaired is 80 fastened upon the iron strips 17, the workman can turn the engine to the most advantageous position, by simply lifting upon either of the angle bars 15, thus rotating the annuli upon the arch-shaped members 12. 85 This turning of the engine can be accomplished with the least exertion and effort, while the friction between the annuli and the annular members 12 due to the weight of the engine will support the work in any adjusted position.

What is claimed is:

1. An engine repair stand comprising a base, standards rising from the corners thereof, arcuate shaped members connecting the end pairs of standards, an annulus mounted for rotation upon each of said arcuate shaped portions, spaced parallel bars connecting the annuli and constituting a support for the work, and flanges formed on 100 said annuli and arranged at the opposite sides of the arcuate shaped portions for preventing endwise movement thereof.

2. An engine repair stand comprising a base, standards rising from the corners 105 thereof, depending arcuate shaped portions

connecting the end pairs of standards, an annulus rotatably mounted on each of said arcuate shaped portions, spaced parallel angle bars connecting the annuli and provided with a longitudinal series of apertures, substantially L-shaped straps associated with each of said bars and having

their longer limbs apertured and extended inwardly, said straps of the respective bars being in horizontal alinement, and flanges 13 formed on each annulus to prevent endwise movement thereof.

In testimony whereof I affix my signature.

ALEX F. AMELUNG.
